(57) **CLAIM**

The ornamental design for a portion of a lighting fixture, as shown and described.

DESCRIPTION

FIG. 1 is a bottom perspective view of a portion of a lighting fixture showing our new design;

FIG. 2 is another bottom perspective view thereof with the end cap and end shield shown in broken lines removed;

FIG. 3 is bottom plan view thereof;

FIG. 4 is a side elevational view thereof, the other side being a mirror image;

FIG. 5 is a top plan view thereof; and,

FIG. 6 is an enlarged cross-sectional view thereof taken long lines 6—6 in FIG. 4.

FIGS. 1—5 are broken away to indicate indeterminate length. The broken lines shown in FIGS. 1—6 are for illustrative purposes only and form no part of our claimed design. The broken lines in FIG. 5 also represent the bounds of the claimed design; the regions within these broken lines form no part of our claimed design.
